DETACHABLE SHIELD FOR FOUNDATION GARMENTS

Edward R. Sutter, Chicago, Ill., assignor to Beau-T-Form Foundations, Inc., Chicago, Ill., a corporation of Illinois

Application October 3, 1942, Serial No. 460,607

3 Claims. (Cl. 128—149)

The invention relates to a detachable shield for a foundation garment and has as a general object to provide a new and improved shield of the character described.

A more particular object is to provide a shield having downwardly depending portions to lie between the legs of the wearer and means anchoring around the leg holding each depending portion smoothly in position to prevent the chafing resulting from rubbing of the legs directly one on the other.

Another object is to provide a shield that is shaped between the legs, that is, a shield having a main or central piece conformed to the space between the legs.

Another object is to provide a shield that is yieldable through the center, that is, longitudinally in a front to rear direction.

A further object is to provide a shield having a longitudinally yieldable main or central piece and depending chafe preventing portions also yieldable in the same direction.

Still another object is to provide a shield composed of a plurality of pieces of material cut to give a smooth, perfect fit and at the same time save material.

Other objects and advantages will become apparent from the following description taken in connection with the accompanying drawing, in which:

Fig. 1 is a perspective view of a shield embodying the features of this invention illustrated in the position it assumes on a wearer.

Fig. 2 is a transverse sectional view taken approximately along the line 2—2 of Fig. 1.

Fig. 3 is a side elevational view.

Fig. 4 is a view on a reduced scale showing the shield spread out as nearly flat as possible.

While the invention is susceptible of various modifications and alternative constructions, it is here shown and will hereinafter be described in a preferred embodiment. It is not intended, however, that the invention be limited thereby to the specific disclosure made but on the contrary it is intended to cover all modifications and alternative constructions falling within the spirit and scope of this invention as defined in the appended claims.

As shown herein for purposes of disclosure, the shield comprises generally a main or central piece, generally designated 10, means at the front and the rear for detachably securing the shield to a foundation garment, chafe preventing portions, generally designated 11, and anchoring means therefor, generally designated 12. The central piece 10, as best seen in Fig. 4, is shaped to conform to the space between the legs to have the shield fit smoothly and comfortably and prevent folds of excess material which would itself chafe the wearer. To that end, the piece 10 is

made narrow at the midpoint and flares curvedly outwardly in hour glass fashion in both directions from the midpoint. The piece is symmetrical about a longitudinal center line, but not about a transverse line through the midpoint, the flare being somewhat greater in the rear half of the piece to provide necessary fullness. By way of example, the piece 10 is at its front end 13 here shown as in excess of twice the width at the midpoint, while at its rear end 14 as in excess of three times the width at the midpoint.

In addition to being thus shaped, the piece 10 is so constructed or of such material as to have limited stretch in a longitudinal direction. Herein this is accomplished without the use of rubber by employing a material so woven or knit as to have this resiliency in a longitudinal direction. Preferably the material has substantially no give in a transverse direction. In the present instance, the material is a jersey woven from threads composed of some one or more of the cellulose derivatives.

To support the central piece 10 detachably from a foundation garment, the front end 13 is provided with fasteners which are here shown as buttons 15. Three such buttons are here shown and they are sewn directly onto the piece 10, which along the edge is bound and reinforced by a tape 16. Cooperating with the buttons 15 is a buttonhole strip 17 usually secured as by sewing to the foundation garment. At the rear, the piece 10 has attached to each corner, through the medium of a short piece of elastic 18, a tab 19 having a buttonhole 20 formed therein. These tabs 19 cooperate with buttons on the foundation garment.

A foundation garment in performing its function of slenderizing the hips and upper thigh naturally presses the flesh of the thigh inwardly. Even in the case of a woman of average build, and particularly in stout and fat women, this causes the flesh on the inside of the thighs to rub together and chafe. To prevent such direct contact of the flesh is an important feature of this shield. This function is performed by the portions 11. One such portion is sewn by an external "Merrow" seam 21 to each curved side of the central piece 10. Each portion 11 is composed of a piece of material having a straight lower edge, ends each cut on an inwardly angling bias, and a top edge that is curved upwardly so that it may follow the central piece from its low midpoint upwardly to its ends and still hang smooth and unwrinkled. Like the piece 10, each piece 11 has a limited stretch longitudinally and is, of course, preferably made of the same material as the piece 10. In this way, the pieces 11 do not interfere with the yielding of the central piece.

With the rubbing to which the portions 11 are

subjected while the wearer is walking, there is a great tendency for the portions to fold or roll up which then is worse than no portion 11 at all. To prevent this, the anchoring means 12 is provided. This means consists in effect of extensions 22 and 23 of the piece 11, of a length enabling them to extend around the thigh and be secured together. While these extensions might be integral with the piece 11, they preferably are separate pieces sewn to the ends of the piece 11. Each extension is composed of a piece of material generally triangular in shape with a straight bottom edge, a wide end cut on the bias and a rapidly downwardly curving third side. The bias cut, wide end of the extension is sewn to the end of the piece 11 and the other end is squared. On their squared end the extensions 22 and 23 carry cooperating fastener means 24 and 25, respectively. At this point, each extension is also preferably reinforced by a strip 26 sewn thereon. One advantage of separate rather than integral extension pieces 22 and 23 is the bias cut, as will presently be enlarged upon. Another advantage is the saving in material.

While the bias cut of the extensions 22 and 23 is complementary to the bias cut of the piece 11, the angle of the bias is not quite as great, with the result that the completed thigh encircling structure has a slight taper to conform to the taper of the thigh. The extensions 22 and 23 have a stretch in a longitudinal or circumferential direction. Any suitable material may be employed but preferably a jersey material the same as that composing pieces 10 and 11 is used. The various pieces are, of course, proportioned in size in accordance with the size of the shield as a whole. Preferably the extensions 22 and 23 are of such length that when fastened together the thigh will be snugly surrounded. This will anchor the pieces 11 firmly and smoothly in place, holding the flesh out of direct contact. Due to the circumferential stretch of the pieces 11, 22 and 23 plus the bias construction thereof, the piece 11 is thereby so smoothly and tightly held against the thigh that there is no wrinkling or rolling up of the pieces. In fact, there is substantially no relative movement between the piece 11 and the thigh on which it is worn; this relative movement and friction contact being taken by the comparatively slippery, jersey material pieces 11. The shield is throughout its periphery preferably bound and reinforced with a binding 27.

It is believed apparent from the foregoing that I have perfected a vastly improved, detachable shield for a foundation garment. This shield has a shaped construction to eliminate all excess material that might either bulk or be uncomfortable. At the same time the shield allows of complete freedom of action because of the novel use of stretchable material. Above all, the construction of the shield assures that the chafe preventing portion remains smoothly and firmly in position.

I claim as my invention:

1. A detachable shield for a foundation garment comprising, in combination, a central piece of jersey material extending from front to rear of the shield and stretchable in that direction, said piece being narrowest at an intermediate point and becoming progressively wider in both directions away from the intermediate point, means at each end of said piece adapted to cooperate with means on the front and the back of a foundation garment for removably attaching said piece to the garment, an elongated piece of jersey material sewn to each side of said cen-

tral piece to depend downwardly therefrom when the shield is suspended from a foundation garment, each of said elongated pieces having a straight bottom edge, a top edge equal in length to the side of said central piece and curving upwardly at its ends, and end edges cut on an inwardly angling bias, said pieces being stretchable longitudinally, a pair of extension pieces sewn to the ends of each elongated piece for anchoring the same snugly against the thigh of the wearer, each extension piece being generally triangular in shape with a straight bottom edge and an end edge sewn to the end of said elongated piece cut on the bias, and cooperating fastening means on the free end of said extension pieces for securing the same snugly about the thigh of the wearer, said extension pieces having a stretch circumferentially.

2. A detachable shield for a foundation garment comprising, in combination, a central piece of material extending from front to rear of the shield and stretchable in that direction, said piece being narrowest at an intermediate point and becoming progressively wider in both directions away from the intermediate point, means at each end of said piece adapted to cooperate with means on the front and the back of a foundation garment for removably attaching said piece to the garment, an elongated piece of material sewn to each side of said central piece to depend downwardly therefrom when the shield is suspended from a foundation garment, each of said elongated pieces having a straight bottom edge, a top edge curving upwardly at its ends, and end edges cut on an inwardly angling bias, said pieces being stretchable longitudinally, a pair of extension pieces sewn to the ends of each elongated piece for anchoring the same snugly against the thigh of the wearer, each extension piece being generally triangular in shape with a straight bottom edge and an end edge cut on the bias, and cooperating fastening means on the free end of said extension pieces for securing the same snugly about the thigh of the wearer, and extension pieces having a stretch circumferentially.

3. A detachable shield for a foundation garment comprising, in combination, a central piece of material extending from front to rear of the shield and stretchable in that direction, said piece being narrowest at an intermediate point and becoming progressively wider in both directions away from the intermediate point, means at each end of said piece adapted to cooperate with means on the front and the back of the foundation garment for removably attaching said piece to the garment, an elongated piece of material sewn to each side of said central piece to depend downwardly therefrom because the thighs of the wearer when the shield is suspended from a foundation garment, each of said elongated pieces having its end edges cut on an inwardly angling bias and being stretchable longitudinally, a pair of extension pieces sewn to the ends of each elongated piece for anchoring the same snugly against the thigh of the wearer, each extension piece being generally triangular in shape with a wide end edge by which it is sewn onto said elongated piece also cut on the bias, and cooperating fastening means on the free end of said extension pieces for securing the same snugly about the thigh of the wearer, said extension pieces having a stretch circumferentially.
